UNITED STATES PATENT OFFICE

2,401,586

EXCESS VOLTAGE PROTECTIVE DEVICE

Sidney R. Smith, Jr., Pittsfield, Mass., assignor to
General Electric Company, a corporation of
New York

Application April 18, 1942, Serial No. 439,507

2 Claims. (Cl. 200—115)

1

My invention relates generally to excess voltage protective devices and particularly to means for preventing foreign objects from interfering with the correct operation of such protective devices.

Protective devices for protecting against high-voltage surges, such as the well-known expulsion protector tube or other forms of lightning or surge arresters are often used in connection with the protection of transformers, a circuit-interrupting device, such as a fuse cutout or the like, being connected in series with the line side of the transformer and the surge arrester being connected with one terminal of the fuse cutout to provide a path to ground for voltage surges. Since the support for the surge arrester provides a space for foreign objects, such as birds, to alight, service outages frequently result from arc-overs which have been initiated by the foreign objects establishing a low-resistance path from one of the fuse terminals to ground. For example, birds which alight on the supporting means for the surge arrester are attracted by the adjacent bright metal terminal parts and initiate an arcover by pecking at these parts.

It would be desirable to provide means for guarding against this danger. Accordingly it is an object of my invention to provide a new and improved surge arrester and support therefor which is substantially birdproof.

It is another object of my invention to provide an expulsion protective type surge arrester which may be readily removed by a service man without danger to life or property.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is an elevational view of a fuse cutout and associated birdproof surge protector embodying my invention, Fig. 2 is a view partly in section taken on line 2—2 of Fig. 1, Fig. 3 is an exploded view of a portion of the surge protector and support therefor, and Figs. 4, 5, and 6 are modifications of birdproof surge protectors embodying my invention.

Referring now to Figs. 1 to 3 of the drawing, I have illustrated the birdproof surge protector embodying my invention as associated with a specific type of fuse cutout. It should be understood, however, that the specific type of fuse cutout illustrated is merely for the purpose of illustration since my invention is applicable to any circuit-interrupting or other electrical device. The open type fuse cutout, generally indicated at 10 in Figs. 1 and 2, comprises a supporting insulator 11 which

may be suitably supported from a pole carrying the transmission line or the like, not shown, as by a supporting strap or hanger construction, generally indicated at 12, which is adapted to surround a central portion of reduced diameter 13 of the insulator 11. The details of the hanger construction 12 form no part of the present invention but are disclosed and claimed in my concurrently filed copending application Serial No. 439,506 filed jointly with Ralph S. Bennett, and assigned to the same assignee as the present application. Insulator or supporting structure 11 supports in spaced relationship upper terminal assembly 14 and lower terminal assembly 15 which are preferably of the type disclosed and claimed in the above-mentioned copending application and these terminal assemblies 14 and 15 are preferably connected to suitable line terminals.

The electrical circuit between terminal assemblies 14 and 15 is completed through upper fuse link supporting arm 16, a fuse link generally indicated at 17, lower fuse-link supporting arm 18, and conducting member 19 which pivotally supports lower fuse-link supporting arm 18 and electrically interconnects it with lower terminal assembly 15. A suitable spring 20 is provided for biasing pivotally mounted lower fuse-link supporting arm 18 in a counterclockwise direction as viewed from Fig. 2, thereby providing tension on fuse-link 17 to cause rapid separation of the fuse-link terminals upon rupture of the fusible element. Although I have disclosed upper and lower fuse-link supporting arm 16 and 18, respectively, as constructed of rather rigid material with spring means 20 for causing separation of these supporting arms upon rupture of the fuse link, it should be understood that these supporting arms might be constructed of inherently resilient material in which case it would be unnecessary to provide additional spring means, such as 20.

Fuse link 17 preferably comprises a fusible element and, if necessary, a parallel strain wire, not shown, enclosed within an insulating tube 21. The ends of the fusible element which may be paralleled by a strain wire are connected to the ends of flexible cable portions 22, one of which is connected to upper fuse-link terminal 23 and the other to lower fuse-link terminal 24. These fuse-link terminals are preferably provided with a loop or other means for inserting a switch stick to permit ready re-fusing of the cutout in a manner which will be obvious from Figs. 1 and 2. Upper and lower fuse-link supporting arms 16 and 18 are provided with spring-biased clamping or jaw members 25 and 26, respectively. The fuse link 17 may have the upper and lower ends thereof inserted in these clamping members which are constructed to facilitate ready insertion and removal of the fuse links 17. The fuse cutout described heretofore forms no part of the present invention

and is included merely to aid in understanding the application of my birdproof surge arrester associated therewith.

Since the hanger construction 12, as shown in Figs. 5 and 6 of the above-mentioned copending application, is usually grounded, it is readily adaptable to being used with a surge protector which may have one terminal connected thereto and, accordingly, in Fig. 1, I have shown a conducting support of member 27 having a double U-shaped end 27' identical with the conducting support shown in Fig. 6 of the above-mentioned copending application which is particularly adaptable for use with a hanger construction, such as 12. Conducting support or member 27, preferably extends at right angles from insulator 11 with reference to upper and lower fuse-link supporting arms 16 and 18. Any suitable surge arrester may be supported by member 27 and, accordingly, I have illustrated a surge arrester of the expulsion protector tube type disclosed and claimed in United States Letters Patent 2,050,397. Such an expulsion protector tube type of surge arrester comprises a pair of spaced electrodes, one of which is connected to the line to be protected and the other to a suitable ground. To insure early extinguishment of the arc drawn between the electrodes due to a voltage surge, a dielectric structure is provided surrounding the gap between the electrodes, thereby confining the arc space to maintain a high arc voltage. This dielectric structure is furthermore composed of a material capable of evolving large quantities of substantially non-ionized gas when in close proximity to an arc discharge. Such an expulsion protector tube type surge arrester is shown in Fig. 1 in which the dielectric structure comprises a tube 28 having a conducting terminal 29 at one end thereof and a conducting terminal 30 at the other end (see Fig. 3). These terminals 29 and 30 are preferably threadedly mounted on the dielectric structure comprising tube 28. In order rapidly to extinguish any arc drawn between the electrodes, not shown, contained within the tube 28, the bore of the tube and, consequently, the electrode within this tube bore is very small. If terminal 29 were connected directly to the high-voltage line to be protected, difficulties due to corona discharge from this small electrode would occur and, to prevent this, conducting terminal 29 of the expulsion protector tube type of surge arrester is not connected directly to terminal 14 but instead has a gap 31 interposed between terminal 29 and an electrode 32, which, in turn, is connected to terminal assembly 14. Electrode 32 preferably comprises a bent rod, whereby the setting of gap 31 may be adjusted by merely sliding the rod in terminal assembly 14. With this arrangement, terminal 29 and the electrode associated therewith contained within tube 28 are normally maintained at a low potential relative to the potential of the electrode 32. The terminal 30 of the expulsion protector tube type of surge arrester illustrated in Figs. 1 to 3 is electrically connected to conducting support 27, which, in turn, is connected to ground through hanger construction 12.

In order to permit ready removal and replacement of tube 28 and the associated terminals 29 and 30, terminal 30 is preferably provided with two parallel contact faces 33 and diametrically opposed trunnions 34. Conducting support or member 27 on the other hand is provided with cooperating contact portions 35 for engaging with parallel contact faces 33. Also, cooperating contact portions 35 include trunnion receiving

notches 36 which open in a downwardly direction so that the trunnions 34 may be inserted therein by an upward movement. The contact faces 33 of terminal 30 are preferably provided with indentations 37 into which embossed portions 38 of cooperating contact members 35 may be inserted to latch terminal 30 into firm conducting engagement with cooperating contact portions 35 supported by conducting member 27. To insure good contact between these members, cooperating contact portions 35 are preferably somewhat resilient to grasp closely contact faces 33. A suitable hook or switch stick receiving portion 39 may be associated with upper terminal 29 to facilitate ready removal of the expulsion protector tube surge arrester comprising tube 28 and terminals 29 and 30. By merely pulling outwardly on hook 39, tube 28 will be rotated with trunnions 34 as a pivot so as to force embossed portions 38 out of indentations 37 whereupon tube 28 and associated terminals 29 and 30 are released and may be completely removed from conducting support 27. To insert the expulsion protector type surge arrester in position on conducting support 27, a lineman would simply move tube 28 and its associated terminals, supported on a switch stick by hook 39, in an upward direction until trunnions 34 engage notches 36 after which the tube would be rotated about trunnions 34 until latched by means of embossed portions 38 and indentations 37. It should be understood that operation of the expulsion protector tube type of surge arrester illustrated entails an upward force on support 27 due to the rapid expulsion of arc gases from tube 28. The removable mounting arrangement for tube 28 limits the upward movement of the tube inasmuch as trunnions 34 are restrained from moving upward by notches 26. With my new and improved arrangement, the setting of gap 31 remains constant at a fixed distance and it is, consequently, possible to remove a surge arrester, such as illustrated, from service and replace it with a new one of the same standard dimensions, maintaining the setting of gap 31 without additional adjustment being required. Furthermore, this replacement may be accomplished while the associated transmission line is still energized.

With the arrangement described thus far, it will be obvious from Fig. 1 that, without additional means, foreign objects, such as birds might alight on conducting support 27 and peck at electrode 32, thereby initiating an arcover with a resultant service outage. To prevent this, I provide in accordance with my invention a bird guard 21' which might be molded from a plastic material, such as aceto butyrate or the like, and which is so shaped that it could readily be snapped over the edges of arm 27. With this arrangement foreign objects, such as birds, can no longer alight on conducting support 27, thereby eliminating any difficulty in this regard.

Although in Figs. 1 to 3, I have illustrated a surge arrester associated with a fuse cutout, such a surge arrester might be supported adjacent the high-voltage terminal of a transformer, for example, and, in Fig. 4 I have chosen to illustrate a modification of my invention applied to the high-voltage bushing 40 of a transformer, not shown. A suitable conducting support 41 of relatively short length is welded or otherwise fastened to the grounded transformer tank, only a small conductor portion 42 being shown in Fig. 4. A suitable expulsion protector tube type of surge arrester comprising tube 43 and terminals 44 and 45, respectively, has the lower terminal 45 there-

of electrically connected to conducting support 41 as by means of hollow bolt 46 passing through a slotted opening 47 in conducting support 41. The opening in bolt 46, not shown, permits gases to escape from tube 43 during operation thereof. With this arrangement, the expulsion protector tube type of surge arrester is mounted in a substantially vertical position to form a gap 48 between upper tube terminal 44 and an electrode 49, electrically connected to the transformer terminal associated with bushing 40. Adjustment of the gap 48 may be accomplished by moving tube 43 horizontally on conducting support 41, which may be accomplished by virtue of the slot 47. Also because of the relatively short arm 41 and the vertical position of the expulsion protector tube type surge arrester, the arrangement of Fig. 4 is substantially birdproof since there is insufficient space for a bird to alight on arm 41. Further to insure such birdproofing, it may be desirable to use a bushing terminal guard 50 which may be substantially identical to that disclosed and claimed in United States Letters Patent 2,263,319, granted November 18, 1941, upon an application of E. D. Treanor, and assigned to the same assignee as the present application. I have discovered that, by using the short conducting support 41 of Fig. 4, the surge arrester may be mounted on the transformer bushing and the entire unit including the transformer shipped in a standard crate, which is not possible when a longer conducting support 41 is utilized.

To prevent insects from entering the lower open end of tube 43 thru the opening in hollow bolt 46 it may be desirable to provide an insect guard such as 51 comprising a flexible metal plate which is supported by bolt 46 and bent over to close the opening at the bottom of the expulsion protector tube. This will prevent insects from building their nests within the bore of the tube prior to the first tube operation, and since flexible insect guard 51 will be blown downwardly by the expelled gases when the tube operates, it will also serve as an indicator with respect to whether or not the surge arrester has operated. Such a guard might also serve the additional purpose of a name plate for the device.

In Fig. 5, I have shown a modification of the arrangement disclosed in Fig. 4 with the corresponding parts thereof designated by the same reference numerals. Instead of using the short supporting arm 41 as shown in Fig. 4, a longer supporting arm 41' is used, in which case, tube 43 is mounted at an inclined position somewhat similar to that disclosed in Fig. 1 rather than the more nearly vertical position indicated in Fig. 4. To permit adjustment of gap 48, electrode 49' comprises a bent rod similar to rod 32 of Fig. 1. To prevent birds from roosting or alighting on conductor support 41', I provide a suitable insulating guard 52 which substantially fills the space between bushing 40 and tube 43 and which is suitably fastened as at 53 to conducting support 41'.

It might be desirable to provide such a surge arrester in connection with the conventional enclosed type of fuse cutout such as is disclosed in United States Letters Patent 2,081,813, granted May 25, 1937, upon an application of B. R. Hermann, and assigned to the same assignee as the present application. Accordingly, in Fig. 6, I have disclosed such an enclosed type of cutout generally indicated at 54 which may be

supported from a crossarm or the like by means of a hanger 55 cemented to the rear wall of the cut-out housing. An expulsion protector tube type of surge arrester comprising tube 43 and terminals 44 and 45 may be supported from hanger 55 by means of a strap 56 electrically connected to lower terminal 45. A suitable gap 57 may be provided between terminal 44 and an electrode 58, which may consist of a straight rod bent at one end, the rod extending into the enclosed housing of the cutout through opening 59 and being electrically connected to a line terminal within the housing. The setting of gap 57 can then be adjusted by merely twisting the rod-shaped electrode 58. With this arrangement, the surge arrester may be mounted directly on the cutout hanger, thereby not only simplifying the mounting hardware but eliminating any necessity for mounting the surge arrester directly to the crossarm. The supporting strap 56 may be provided with a grounding terminal 60. By properly covering strap 56 with some sort of insulating jacket, it will be impossible for a bird to initiate an arcover by alighting thereon and engaging electrode 58.

While I have shown and described several embodiments of my invention, I desire to have it understood that the specific forms shown are merely illustrative and I intend in the appended claims to cover all such changes and modifications as fall within the true spirit and scope of my invention.

What I claim as new and desire to secure by Letters Patent of the United States, is:

1. In combination, an insulating support, a supporting arm of conducting material extending outwardly with respect to said insulating support, said supporting arm including contact portions having trunnion-receiving notches therein, a surge arrester of the expulsion type including a terminal having trunnions extending therefrom adapted to be received by said trunnion-receiving notches, latching means for latching said surge arrester in a predetermined position on said support so that said terminal of said surge arrester is electrically engaged by the contact portions of said supporting arm, and a guard of insulating material mounted on said supporting arm between said insulator and said surge arrester for preventing foreign objects such as birds from standing on said supporting arm and short circuiting said surge arrester.

2. The combination with an electric switching device having an insulating support and a pair of spaced terminal contacts, means for supporting an electric switching element from said support and electrically connected between said contacts, a supporting arm of conducting material extending outwardly with respect to said insulating support, said supporting arm including contact portions having downwardly opening trunnion-receiving notches therein, a surge arrester of the expulsion type including a terminal having an opening therein from which gases may be expelled upon operation of said surge arrester and including trunnions extending therefrom adapted to be received by said trunnion-receiving notches, and means including embossed portions for latching said surge arrester in a predetermined position on said support by rotating said surge arrester about said trunnions in said trunnion-receiving notches.
